UNITED STATES PATENT OFFICE.

CHARLES H. VAN SLYCK, OF PHILADELPHIA, PENNSYLVANIA,
ASSIGNOR TO THE GENERAL ELECTRIC COMPANY, A CORPO-
RATION OF NEW YORK.

ELECTRIC TIME-SWITCH.

No. 832,761.

Specification of Letters Patent.

Patented Oct. 9, 1906.

Application filed October 9, 1899. Serial No. 733,007.

To all whom it may concern.

Be it known that I, CHARLES H. VAN SLYCK, a citizen of the United States, residing at Philadelphia, county of Philadelphia, State of Pennsylvania, have invented certain new and useful Improvements in Electric Time-Switches, of which the following is a specification.

This invention relates to time-switches for electric circuits, and a switch constructed in accordance therewith is adapted to have its opening and closing movements controlled by a chronometer in order to regulate automatically the supply of current to various translating devices at predetermined intervals.

As an illustrative example one of many structures in which the invention may be embodied is shown in the drawings, of which—

Figure 1 is a full face view of the interior of the casing, showing the operating mechanism. Figs. 2 and 3 are lateral and plan views, respectively, of the same; and Fig. 4 is the circuit-diagram.

Certain features of the invention are not limited in their application as embodiments of a time-switch as above described, but may be embodied in any electrically-operated switch and are useful in still other relations.

A is a chronometer or clock-movement actuated in any suitable manner, as by a spring or electricity, and insulated from the working circuits. The working spindle of A makes only one complete rotation in twenty-four hours. A thumb-screw 1 holds springs B to the rotating chronometer member at selected angles, one of the springs being thereby adapted to close and the other to open the working circuit at predetermined intervals. Each spring is successively put under tension by engagement with a rigid pin C, and when it is carried past the pin it impinges against the lever D, pivoted at 2 to the frame F, whereupon the roller 3, supported in a dependent of the lever below the pivot, moves up the incline of the inverted V of the spring 4. This spring is secured to the frame F, and the contact E, carried by and insulated from the lever D, is snapped into engagement with the contact E', which is carried by and insulated from the frame F

and connected through the magnet-coil H to one pole Q', Fig. 4, of the switch, to which is connected one side of the generator. Any number of switch-actuating electromagnets could be connected in series in the circuit thus established. The contact E is electrically connected to another pole Q, Fig. 4, of the switch, to which pole is connected a lead from the other side of the generator G. If these contacts E and E' close a circuit derived either from the generator-circuit or an auxiliary source cut out later, the coil H will be energized and the core I drawn down against the tension of the adjustable spring 4^a on the lever J, which is pivoted at 5. Pivoted to J at 6 is a link K, which is pivoted at its other end 7 to a supporting-rod P, loosely mounted on a rotatable spindle 9. A pawl L is pivoted at 10 to the rod P, and when the link K is depressed the pawl moves the ratchet-wheel M, secured to the spindle 9, one notch downward on the left, whereupon a spring-dog 11 engages with a next or "on" notch in a stop-wheel N, also secured to the spindle 9. A disk O, of insulating material, Fig. 3, is secured to the spindle 9 and carries a series of pins of good conducting material arranged in a circle. Referring to Fig. 4, it may be seen that with the spindle 9 at this point in its rotation two pins make contact simultaneously, the one beneath the plane of the spring-contacts engaging with the spring-contact Q, connected to one side of the line, and the spring-contact R, connected to one side of the circuit of the translating devices X, and the other pin above the plane of the spring-contacts engaging with the spring-contact Q', connected to the other side of the line, and the spring-contact R', connected to the other side of the translating-device circuit. The latter circuit is now closed.

Adjustably mounted on the magnet-core I by means of a set-screw U, as shown, is a sleeve S, carrying a pin or dog T, which is adapted to engage the lever D in the downward movement of the core after the spring-dog 11 has started down the next notch in the stop-wheel N and before the magnet has been injured by the current to raise the contact E from the contact E', the roller 3 depressing the spring 4, which snaps it back and holds the contact against the pin C. The core I will now rise under the tension of the

spring 4^a, as the coil H is no longer energized, and the apparatus is ready for the operation of opening the switch, which is accomplished in a similar manner to that described for its closing by the engagement of the other spring B with the pin C. At the end of this operation the spring-dog 11 engages in the next or "off" notch of the stop-wheel N, and, Fig. 4, all the pins P are separated from the spring 10 switch-contacts.

In Fig. 1 is shown the mode of connecting the outside circuits to the apparatus, which are not, as shown for clearness in Fig. 4, direct from the generator to the switch-contacts. An insulating-strip 12 is secured to the casing, and upon this are mounted the pieces 13, each provided with binding-posts, one for the outside circuit and one for the corresponding switch-contact binding-post. 15 20 25 30 35 40 45 50 55 60 65 70 75 80 85 90 95 100 105 110 115 120 125 130

14. The contacts E and E' are engaged at the predetermined time whether there is current in the line or not, and they remain in contact until current is turned on, when the switch is opened or closed, as has been predetermined. If the current is cut off at the station, the switch will remain in the position to which it has previously been moved, and at the predetermined time the contacts E and E' will engage, and then the switch will be moved to the new position as soon as current is turned on.

What I claim as new, and desire to secure by Letters Patent of the United States, is—

1. In a circuit-controlling device, the combination with a main switch for said circuit, of an electromagnet for actuating said main switch, an auxiliary switch controlling the circuit of said electromagnet, means for periodically closing said auxiliary switch, and means for opening said auxiliary switch when the electromagnet actuates the main switch.

2. In a circuit-controlling device, the combination with a main switch, of a solenoid, a core for said solenoid, connections between said main switch and said core whereby said switch is operated when the solenoid is energized, an auxiliary switch with a movable contact controlling the circuit of said solenoid, means for periodically closing said auxiliary switch, and a lost-motion connection between said core and said movable contact for opening said auxiliary switch at the end of the movement of said core to operate the main switch.

3. In a controlling device for an electric circuit, a main switch, a solenoid, a core for said solenoid actuating said switch, an auxiliary switch controlling the circuit of the solenoid, means for yieldingly holding said auxiliary switch either open or closed, means for periodically closing said auxiliary switch, and a lost-motion connection between said auxiliary switch and said core whereby the auxiliary switch is opened when said core moves and actuates the main switch.

4. In a circuit-controlling device, the combination with a main switch having a movable contact, of a solenoid, a core therefor, means connected to the core for actuating the movable contact to open or to close said main switch when the core is attracted by the solenoid, an auxiliary switch controlling the circuit of the solenoid, means for periodically closing said auxiliary switch, and connections between said auxiliary switch and said core whereby said auxiliary switch is opened when the core is attracted by the solenoid.

5. In a circuit-controlling device, the combination with a main switch having a movable contact, a solenoid, a core therefor, a ratchet-wheel for actuating said movable contact, a pawl engaging said ratchet and actuated by said core so that the movement of the core in one direction causes the pawl to engage with the ratchet-wheel and open the switch and a second similar movement of said core causes the pawl to engage the ratchet-wheel and close the switch, an auxiliary switch controlling the circuit through the solenoid, means for periodically closing said auxiliary switch, and connections whereby the movement of the core in a direction to actuate the main switch opens the auxiliary switch.

6. The combination with a main switch having a movable contact, of a solenoid, a core for said solenoid, connections between said core and said contact for moving the main switch from open to closed position, or vice versa, by a single movement of the core in one direction, an auxiliary switch for controlling the circuit through the solenoid, a clock for closing said auxiliary switch, and a connection between said core and said auxiliary switch whereby the auxiliary switch is opened at the end of the movement of the core to operate the main switch.

7. In a circuit-controlling device, the combination with a main switch for said circuit, an electromagnet and an armature for said electromagnet for actuating said main switch, of an auxiliary switch having a pivoted contact for controlling the circuit of said electromagnet, a clock, means actuated by said clock to strike said contact and move it to position to close the electromagnet-circuit, an opening through said contact, a rod carried by said armature and extending through said opening, an adjustable sleeve on said rod engaging said contact to move it to position to open the circuit when the armature approaches the electromagnet, and means for yieldingly holding said contact in either position.

8. In a circuit-controlling device, the combination with a main switch having a rotatable contact and a shaft upon which said contact is mounted, of an electromagnet, an armature for said electromagnet, a pivoted le-

ver having one end connected to said armature, a spring connected to the other end of said lever and normally holding said armature away from the electromagnet, a ratchet-wheel fixed to said shaft, a pawl connected to said lever and engaging said ratchet-wheel so that said wheel is rotated when the armature is attracted by the electromagnet, an auxiliary switch controlling the circuit of the electromagnet, a clock for closing said auxiliary switch at predetermined intervals, and a lost-motion connection between said auxil-

iary switch and said armature whereby the auxiliary switch is opened when the armature is attracted but is not affected by the movement of the armature away from the electromagnet. 15

In witness whereof I have hereunto set my hand this 6th day of October, 1899.

CHARLES H. VAN SLYCK.
